United States Patent Office.

G. F. HAMMER, OF CINCINNATI, OHIO.

Letters Patent No. 76,755, dated April 14, 1868.

IMPROVEMENT IN MACHINES FOR POLISHING WOOD.

The Schedule referred to in these Letters Patent and making part of the same.

TO ALL WHOM IT MAY CONCERN:

Be it known that I, G. F. HAMMER, of Cincinnati, in the county of Hamilton, and State of Ohio, have invented a new and useful Improvement in Machine for Smoothing Looking-Glass Frames and other articles with sand-paper; and I do hereby declare that the following is a full, clear, and exact description thereof, which will enable those skilled in the art to make and use the same, reference being had to the accompanying drawings, forming part of this specification, in which—

Figure 1 is an end view of my improved sand-papering machine.

Figure 2 is a vertical section, taken in the line x x , fig. 1.

Figure 3 is a detached view of the roller or drum on which the sand-paper is attached.

Figure 4 is a cross-section of the same.

Similar letters of reference indicate corresponding parts.

This invention relates to improvements in the construction of a machine for rubbing and smoothing the edges of looking-glass and picture-frames of wood, and articles of cabinet-ware of any kind; and consists in placing a drum, on which the sand-paper is attached, upon the end of a rotating and reciprocating spindle, and also covering the drum with India rubber, to form an elastic cushion, on which the sand-paper is secured, by gluing or cementing the edges to it in such manner that they shall come together flush with each other, and thus form a continuous surface of sand-paper, which does its work of rubbing or grinding without interruption.

A A represent framing for supporting the machinery, of which a is a horizontal driving-shaft, connected with any prime mover, and carrying a pulley, B, belted to a long pulley, C, on the vertical spindle b , that passes up through the bed or table, D, of the machine, and on its upper end carries the drum E, which is covered with sand-paper, and is shown enlarged in detached views, figs. 3 and 4.

On the driving-shaft a is a worm-gear, e , that engages a spur-wheel, d , on the shaft a' , which extends over to the side of the vertical pulley C, and there carries on its end a plate-crank, e , connected by the rod f with a vibratory cross-head, g , one end of which is connected with the vertical spindle b by a rocking step, h , in order to give it a reciprocating motion, while, at the same time, it revolves, to operate the drum E, for rubbing glass-frames and other articles with sand-paper.

The drum E is covered with an India-rubber cushion, k , on which the sand-paper, i , is secured, by gluing the edges s s together flush with the surface.

The elastic cushion k , thus formed on the drum, affords a base for the sand-paper, which does the work very evenly and nicely, and is far superior, both in execution and durability, to the ordinary wadded-cloth cover on the stationary horizontal drums hitherto in use for sand-papering glass-frames and cabinet-ware.

The great advantage of my improved reciprocating drum consists in the regularity with which the sand-paper moves back and forth upon the frame or other article operated upon, thus rubbing the edges evenly, without scorching the wood or wearing out the sand-paper rapidly.

Having described my invention, what I claim as new, and desire to secure by Letters Patent, is—

The revolving vertical spindle b , drum E, the pulleys B C, belted together, in combination with the cross-head g , connecting-rod f , crank e , spur-wheel d , and worm-gear e , upon shaft a , all arranged to operate as described.

G. F. HAMMER.
